(57) **CLAIM**

The ornamental design for a control unit and visual display for a portable race car signal, as shown and described.

DESCRIPTION

FIG. 1 is an enlarged perspective view of a single hand control unit of a control unit and visual display for a portable race car signal according to the invention;

FIG. 2 is a top plan view thereof;

FIG. 3 is a bottom plan view thereof;

FIG. 4 is a right side elevational view thereof;

FIG. 5 is a left side elevational view thereof;

FIG. 6 is a left end view thereof;

FIG. 7 is a right end view thereof;

FIG. 8 is a front plan view of two hand control units shown in FIGS. 1-7; the two units shown removably mounted to a vehicle steering wheel for the purpose of environment, the steering wheel is shown in broken lines form no part of the claimed design;

FIG. 9 is an enlarged front perspective view of a visual display of a control unit and visual display for a portable race car signal according to the invention;

FIG. 10 is a rear perspective view thereof, the broken lines showing a connector and fasteners for mounting the signaling unit on a vehicle for the purpose of environment, the broken lines form no part of the claimed design;

FIG. 11 is a front elevational view thereof shown in smaller scale, the broken lines showing a connector and fasteners for mounting the signaling unit on a vehicle for the purpose of environment, the broken lines form no part of the claimed design;

FIG. 12 is a rear elevational view thereof, the broken lines showing a connector and fasteners for mounting the signaling unit on a vehicle for the purpose of environment, the broken lines form no part of the claimed design;

FIG. 13 is a right end view thereof, the broken lines showing a connector and fasteners for mounting the signaling unit on a vehicle for the purpose of environment, the broken lines form no part of the claimed design;

FIG. 14 is a left end view thereof, the broken lines showing a connector and fasteners for mounting the signaling unit on a vehicle for the purpose of environment, the broken lines form no part of the claimed design;

FIG. 15 is a top plan view thereof, the broken lines showing a connector and fasteners for mounting the signaling unit on a vehicle for the purpose of environment, the broken lines form no part of the claimed design; and,

FIG. 16 is a bottom plan view thereof, the broken lines showing a connector and fasteners for mounting the signaling unit on a vehicle for the purpose of environment, the broken lines form no part of the claimed design.

The broken line showing of a steering wheel and a second control unit and visual display mounting hardware is
